UNITED STATES PATENT OFFICE

NOEL B. CHARTIER, OF RICHLAND, WASHINGTON.

COMB-CLEANING DEVICE.

1,244,469.

Specification of Letters Patent. Patented Oct. 30, 1917.

Application filed May 2, 1917. Serial No. 165,882.

To all whom it may concern:

Be it known that I, NOEL B. CHARTIER, a citizen of the United States, residing at Richland, in the county of Benton and State 5 Washington, have invented certain new and useful Improvements in Comb-Cleaning Devices, of which the following is a specification.

My invention relates broadly to brushing 10 and scrubbing apparatus and has particular reference to such apparatus adapted for the cleaning of combs, by subjecting the same to the action of movable brush or brushes in the presence of a cleansing liquid.

15 An important object of the invention is to provide apparatus of the above mentioned character, which is adapted to thoroughly clean a comb, in a highly expeditious and convenient manner.

20 A further object of the invention is to provide means for moving the comb into and out of contact with the cleansing liquid, while the same is being subjected to the action of a rotatable brush or brushes.

25 Other objects and advantages of the invention will be apparent during the course of the following description.

In the accompanying drawings forming a 30 part of this specification and in which like numerals are employed to designate like parts throughout the same,

Figure 1 is a side elevation of apparatus embodying my invention,

Fig. 2 is a plan view of the same,

35 Fig. 3 is an end elevation of the same,

Fig. 4 is a transverse sectional view taken on line 4—4 of Fig. 1,

Fig. 5 is a similar view taken on line 5—5 of Fig. 1, and,

40 Fig. 6 is a detail transverse section taken on line 6—6 of Fig. 2.

In the drawings, wherein for the purpose of illustration is shown a preferred embodiment of my invention, the numeral 10 designates a preferably horizontally arranged 45 cleansing liquid holding trough or receptacle, which is open at its top, as shown. At its bottom, the receptacle or trough 10 is provided with longitudinally extending 50 horizontal flanges 11, rigidly secured thereto for insertion within openings or slots 12, formed in the stationary jaw 13 of a clamping bracket. Extending downwardly from the jaw 13 is an L-shaped arm 14 hav-

ing a screw-threaded opening 15, receiving 55 an adjusting bolt 16, which is provided upon its upper end with a coacting lower jaw 17, having swiveled connection therewith. It is thus apparent that the clamping bracket may be conveniently adjusted for securely 60 attaching the receptacle or trough 10 to a portion of the bureau, table or other support.

Formed upon one vertical end of the receptacle or trough 10 is a vertically extending 65 guide 17', having a vertical guideway or socket 18 formed therein, for receiving a vertically reciprocatory rack 19, shown more clearly in Figs. 3 and 4. This rack is provided with a longitudinally extending 70 vertical opening 20, forming spaced vertical bars 21, upon which are formed ratchet teeth 22.

The sets of teeth 22 are adapted to be alternately engaged by a set of teeth or 75 pins 23, rigidly secured to the inner face of a large gear 24, which is pivotally mounted upon the end of the receptacle 10 and turned or rotated by means of a hand crank 25, as shown.

The large gear 24 engages and drives a small gear 26, rigidly mounted upon a stub-shaft 27, journaled within a bearing 28. Secured to the inner end of the stub-shaft 27 is a small gear 29, engaging a gear 30, 85 which engages and drives a gear 31, in an opposite direction to the direction of rotation of the gear 30. The gears 30 and 31 are rigidly mounted upon shafts 32, corresponding ends of which are reduced at 33, 90 and rotatably held within bearings or sockets 34, as more clearly shown in Fig. 2. The opposite ends of the shafts 32 have recesses 35, rotatably receiving longitudinally adjustable bolts or members 36, screw-threaded in stationary bearings 37, as shown. Rigidly mounted upon the shafts 32 are rotatable brushes 38, arranged within the upper portion of the receptacle 10, as more clearly shown in Fig. 5.

100 Means are provided for holding and raising and lowering the comb to be cleaned, comprising a horizontal arm or bar 38' rigidly secured to the upper end of the rack 19. Hinged to the lower edge of the arm 38', 105 upon opposite sides thereof, as shown at 39, are jaws 40, which are yieldingly held in the inner position by means of a spring or

springs 41. The jaws are separated by means of a handle 42, secured to one jaw 40, as shown in Fig. 6.

The operation of the apparatus is as follows:

With the arm 38' in the elevated position, the jaws 40 may be suitably separated, and the comb inserted therebetween. The jaws are then released so that the spring 41 10 yieldingly holds them in the closed position, thus retaining the comb in place therebetween. The receptacle 10 holds a suitable cleaning liquid, such as water, or water and soap. Upon the rotation of the crank 15 25 the teeth 23 alternately engage the sets of teeth 22, thus causing the rack 19 to reciprocate vertically. The comb is therefore carried between the rotating brushes 38, which preferably rotate in opposite directions and have their inner portions traveling downwardly. The comb is brought into and out of contact with the cleansing liquid, while being subjected to the action of the 20 25 rotating brushes.

It is to be understood that the form of my invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. In apparatus of the character described, the combination with a receptacle for holding a cleansing liquid, of a substantially vertically reciprocatory holding device for receiving a comb and movable into and out of the receptacle, a reciprocatory

member secured to the holding device and comprising spaced bars provided upon their inner sides with sets of teeth, guide means secured to the receptacle and receiving the reciprocatory member, a gear pivotally connected with the receptacle and provided upon one side with a set of teeth to alternately engage with the sets of teeth of the spaced bars, a rotatable brush arranged within the receptacle, and a gear connected 45 with the brush and driven by the first named gear.

2. In apparatus of the character described, the combination with a receptacle for holding a cleansing liquid, of a vertically 55 movable device for engagement with a comb to move it into and out of the receptacle, a reciprocatory member secured to the device and arranged at one end of the receptacle and comprising spaced bars carrying sets 60 of teeth with an opening arranged between the sets of teeth, a pivot element secured to said end of the receptacle and passed through said opening of the reciprocatory member, a main gear carried by the pivot 65 element and provided upon its periphery with gear teeth and upon its inner face with a set of laterally projecting teeth to alternately engage with the teeth of said bars, a pair of rotatable brushes arranged within 70 the receptacle, and a pair of gears connected with the brushes and engaging each other, with one gear driven by said main gear.

In testimony whereof I affix my signature in presence of two witnesses.

NOEL B. CHARTIER.

Witnesses:

A. C. ANDERSON,
O. P. ALBERTSON.
